UNITED STATES PATENT OFFICE.

WILLIAM D. RUNDLETT, OF NORTH ANDOVER, MASSACHUSETTS, ASSIGNOR
TO DAVIS & FURBER MACHINE COMPANY, OF NORTH ANDOVER, MAS-
SACHUSETTS.

ADJUSTABLE ECCENTRIC.

SPECIFICATION forming part of Letters Patent No. 717,282, dated December 30, 1902.

Application filed December 28, 1901. Serial No. 87,537. (No model.)

To all whom it may concern:

Be it known that I, WILLIAM D. RUNDLETT, a citizen of the United States, residing at North Andover, in the county of Essex and State of Massachusetts, have invented an Improvement 5 in Adjustable Eccentrics, of which the following description, in connection with the accompanying drawings, is a specification, like characters on the drawings representing 10 like parts.

In condensers wherein aprons extended over rollers are made not only to travel to feed the slivers, but are also reciprocated to condense the slivers, the rollers carrying the 15 aprons are reciprocated by eccentrics—as, for instance, in United States Patent No. 266,414, dated October 24, 1882.

The invention herein to be described has relation to reducing the wear on the eccentrics, and to do this I have devised a new eccentric and have made novel provision for 20 oiling it and also for adjusting the eccentric.

Figure 1, in perspective, shows a sufficient portion of a condenser for carding-machines 25 with my improvements added to enable my invention to be understood. Fig. 2 is an enlarged top or plan view of the eccentric detached. Fig. 3 is a section in the line α , Fig. 2, of the parts shown in said figure with part 30 of a carriage; and Fig. 4 is a section in the line α' .

Referring to the drawings, A represents stationary uprights at the delivery end of the carding-machine; a, horizontal guideways extended therefrom that receive and guide the slide or carriage a' , to which are fastened boxes for sustaining the usual rollers that are surrounded by the condensing-aprons common to said patent.

40 B represents a vertical shaft which may be rotated in any usual manner common in condensers used with carding-machines.

In this class of machine when the vertical shaft B and its usual eccentrics are rotated at 45 a high speed the lubricant is quickly drained from the wearing-surfaces, and unless said surfaces are oiled frequently the eccentrics are liable to be overheated and destroyed, which results in the stopping of the machine 50 until new eccentrics are substituted. I have

aimed to construct the parts in such manner that the oil applied to the eccentrics must traverse the entire wearing-surfaces and finally enter and be retained in a suitable receptacle of such shape or character that the 55 oil may be again returned to the wearing parts whenever the machine is stopped, at which time the parts are liberally flooded with oil. I have aimed to reduce the rapid wearing of the apron-feeding shafts and to reduce the 60 wear on the parts to be described.

The slide or carriage a' (partially shown in Figs. 2 and 3) has a drilled socket a^2 , which is entered by a preferably hollow stud c , extended from an eccentric-strap C, the stud 65 being hollow to receive and retain a quantity of oil to thoroughly lubricate the connection between the strap and slide. The strap near its other end has an annular flange c' of a width to enter an annular groove in an eccentric or block D, surrounding loosely the shaft B and free to be adjusted laterally into any position of eccentricity with relation to said shaft. The inner side of the outer wall of the annular groove in the eccentric or block 70 D has a series of segmental pockets d , and preferably the exterior of said annular flange c' has an oil-groove and annular projection c^2 substantially opposite the series of pockets d , said groove and projection causing the 75 surplus oil to be discharged into the annular pockets and there retained until the eccentric is stopped, at which time the oil returns by gravity to the wearing-surface and again lubricates the same. These pockets are com- 80 posed of a groove interrupted by partitions d^2 , (shown by dotted lines, Fig. 2,) said partitions checking the circular flow of the oil with the flange c' . The strap has an oil-hole 85 at c^3 , which is bored angularly through said flange, as shown in Fig. 3, so that oil applied to the oil-hole which is located in the non-revolving part will be delivered on the outside of the inner wall of said eccentric, where it is difficult to apply the oil when the eccentric is running, owing to the tendency of the oil to fly outwardly, due to centrifugal action. Portions of the strap C extend over the annular groove in the eccentric or block 90 and cover and protect the oil used in lubri- 95 100

cating the eccentric. The eccentric or block is shown as circular externally and as having at its bottom side slots 2, shaped as shown by dotted and full lines, Fig. 2, said slot having leading from it a straight throat 3. The hub f , secured to the shaft B by suitable set-screws 4 and provided at its lower end with a plate f' integral therewith, is extended through the slot 2 in the end of the eccentric or block. 5 The plate f' has, as shown, two slots 5, (see dotted lines, Fig. 2,) through which are passed two screws 6, provided with suitable washers 7, the inner ends of the screws entering threaded holes in the bottom of the eccentric or block at the sides of the slot 2. By loosening the screws 6 the eccentric or block may be moved laterally with relation to the longitudinal center of the shafts B to provide for altering the throw of the eccentric and the 10 slide or carriage, according to the requirements of the machine, a stud 8, rising from the plate f' , sliding at such time in the throat 3 of the eccentric or block. The stud 8 acts as a pointer and coöperates with graduations 15 10 at the upper sides of the throat 3 to indicate the extent of adjustment of the eccentric or block.

Having thus fully described my invention, what I claim as new, and desire to secure by 20 Letters Patent, is—

1. A hub, a block having an annular groove at one side, means to adjust the block on said hub with relation to the longitudinal axis of said hub, and an eccentric-strap having an 25 annular flange entering the said annular groove.

2. A hub, a block having an annular groove at one side, means to adjust the block on said hub with relation to the longitudinal axis of 30 said hub, and an eccentric-strap having an annular flange entering the said annular groove, said strap having an oil-hole leading from the outer side through said flange to the wall of the annular groove nearest the center 45 of said hub.

3. A hub, an eccentric or block having an annular groove provided at the inner side of its outer wall with a series of pockets or spaces

separated by partitions, said pockets receiving and holding oil. 50

4. A hub, an eccentric or block having an annular groove, an eccentric-strap having an annular flange to enter said groove, said strap having a groove to lead oil to the inner wall of said annular groove. 55

5. A hub, an eccentric or block having an annular groove provided in its outer wall with a series of spaces for oil, an eccentric-strap having an annular flange to enter said groove and provided with an oil-discharging groove 60 and ring at its outer face.

6. A hub having at one end a slotted flange and provided with a stud, and an eccentric or block, screws connected with said eccentric or block and free to be moved in said 65 slots to adjust the eccentric or block on said hub, said eccentric having a slot to be entered by said stud to operate substantially as described.

7. A hub, an eccentric or block having an 70 annular groove in one side or face thereof, oil-pockets disposed in the wall of said annular groove, and an eccentric-strap having an annular flange extended from one side or face thereof to engage said groove in the block, 75 said strap extending over the annular groove in the block to cover and protect the oil used in lubricating the eccentric.

8. A hub, an eccentric or block having an annular groove in one side or face thereof, 80 oil-pockets disposed in the wall of said annular groove between the top and bottom thereof, and an eccentric-strap having an annular flange extended from one side or face thereof to engage said groove in the block, said strap 85 extending over the annular groove in the block to cover and protect the oil used in lubricating the eccentric.

In testimony whereof I have signed my name to this specification in the presence of 90 two subscribing witnesses.

WILLIAM D. RUNDLETT.
